UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A SHADE.

Application filed May 17, 1923. Serial No. 6,175. Term of patent 14 years.

To all whom it may concern:

Be it known that I, JOHN BEISWANGER, a citizen of the United States of America, and resident of Steubenville, county of Jefferson, State of Ohio, have invented a certain new, original, and ornamental Design for a Shade, of which the following is a specification.

In the accompanying drawings:

I have illustrated a shade constructed in accordance with my invention.

Referring to the drawings by numerals:

Fig. 1 is a top plan of the shade.

Fig. 2 is a side elevation.

I claim:

The ornamental design for a shade as shown.

Signed by me at Steubenville, Jefferson County, Ohio, this tenth day of May, 1923.

JOHN BEISWANGER.
